CLOSURE FOR WATERPROOF GARMENTS

Louis Ernest Elwin Gossner, San Francisco, Calif.,
assignor to Elro, Inc., San Francisco, Calif., a
corporation of California

Application March 15, 1949, Serial No. 81,460

1 Claim. (Cl. 24—201)

1

This invention relates to a closure for covers, and more particularly to a water-tight closure for water-proof covers, such as garments, or such as would be adapted to enclose boxes, luggage, and the like.

It is an object of this invention to improve water-proof covers of the above-mentioned types by providing for such covers a water-tight closure adapted to also constitute a readily accessible opening for the covers. By way of illustration and not of limitation, the water-tight closure of the invention is particularly adapted to improve the water-tightness characteristic of garments especially intended to be water-proof in nature, such, for example, as are used by members of the armed forces, sportsmen, and the like. In this vein, the invention relates more specifically to the provision of water-tight closure means for pockets, flaps, and other useful openings in such wearing apparel.

It is a further object of the invention to provide a water-tight seal which may be readily incorporated into a cover construction; which may be easily operated by the attendant or wearer to gain access; and which will avoid unnecessary bulkiness of the cover in which it is incorporated.

As distinguished from the well-known and conventional form of water-tight closure operable through the provision of abutting sealing lips, or spaced pairs of such lips, with a slide fastener therebeneath or between the pairs of lips and in alignment therewith, the water-tight closure of the instant invention is operable through the provision of a raisable flap or panel extending over and latterly past the primary fastener joint and into sealing engagement with a member or lip fixed in relation to and laterally offset with respect to said fastener, with said sealing engagement being maintained during all positions of flexure of the closure by secondary fastening means constituted by an oppositely extending flap or panel in overlying relation to the sealing flap adapted to be secured to the cover adjacent the fixed side of the sealing flap.

Other objects and advantages of the invention will be apparent from the following description taken in conjunction with the drawing forming part of this specification, and in which

Figure 1 is a sectional view of a portion of a garment embodying the water-tight closure of the invention;

Figure 2 is a plan view of the closure device of Figure 1 with the cover flap partially turned back; and

2

Figure 3 is a sectional view of the nature of Figure 1, but showing a modification of the closure of the invention.

Referring to the drawing, and specifically to that embodiment of the closure shown in Figures 1 and 2, the numerals 10 and 12 represent panels of a garment, for example, with edges in abutting relation as at 14 between which access is desired to the inner wearing apparel or person of the wearer. In this particular instance it may be assumed that the closure being described is a pocket closure. It is here desired that a water-tight closure be provided for the abutting edges of the panels 10 and 12.

15 Adjacent the inner edge of the panel 10 there is provided a raised shoulder 16 having the characteristics hereinafter described for interlocking relationship with complementary parts of the underside of an overlapping flange 18 on panel 12.

20 It is, of course, anticipated that the panels 10 and 12 shall be fabricated from rubber or other waterproof materials having like properties of elasticity, durability, and adaptability to accepted manufacturing practices.

25 At the inner end or edge of the shoulder 16 carried by panel 10 there is provided a lip 20 which is adapted to be snugly received in a complementary recess 22 of panel 12. This provides a water-tight joint as an offset continuation of the joint or parting line 14 between the inner edges of the panels 10 and 12.

The flange 18 of panel 12 extends beyond the aforementioned water-tight joint constituted by lip 20 and recess 22 to overlie the shoulder 16 of panel 10, and at its outer end it is provided with a downwardly extending flange 24 having an inwardly turned lip 26 adapted to fit snugly within the recess 28 in shoulder 16. The underside of the lip 26 is preferably in sealing engagement with panel 10, as indicated at 30.

From the foregoing it will be understood that there is provided a primary watertight closure at the interfit of the lip 20 with the recess 22, of the panels 10 and 12, respectively, and a secondary seal at the point of interfit of the lip 26 with the recess 28. In the absence of flexure of the garment in normal usage it will be appreciated that the interlocking characteristics of the primary and secondary closures would suffice to exclude water. However, since it is anticipated that the average garment and its various components will be flexed repeatedly during normal usage and wear, it is desirable that suitable retainer means be provided to insure the inter-

locked relationship of the parts hereinabove described. This may take the simplified form of a flexible strip 32, cemented or otherwise secured to the panel 10 as at 34, in the proximity of the secondary closure mentioned above, which strip extends therefrom over both primary and secondary closures and has its opposite edge secured to the panel 12 by means of a conventional slide fastener closure 36 carried in part by strip 32 and in part by a strip 38 which is cemented or otherwise secured to the panel 12. This auxiliary retainer serves to compress the primary and secondary closures and to keep the interlocking parts thereof in proper relationship.

The ends of shoulder 16 and the overlying flange 18 are rounded off at their ends, as indicated at 40 in Figure 2. In order to provide for access to the flange 18, it will be noted that in conjunction with the longitudinally extending slide fastener closure 36 there is also provided a transversely extending slide fastener closure 42 carried in part by the main or cover strip 32 and in part by a strip 44 secured to the base material of the closure contiguous with panels 10 and 12. A second transversely extending slide fastener closure may be provided at the opposite end of slide fastener closure 36, or such second slide fastener may be dispensed with by extending the slide fastener 36 beyond the rounded end of flange 18, in which case the cover strip 32 may be freely turned back as shown in Figure 2 to obtain access to the flange 18.

From the foregoing description it will be appreciated that the operation of the device is extremely simple. Initial separation occurs by manipulation of the slide fastener closures 36 and 42 to free the cover panel 32 which may then be swung back as indicated in Figure 2. Access is thus provided for disengagement of the lip 26 of flange 18 from the recess 28 which may be accomplished by inserting the fingers partially under the flange 24. Flange 18 is then peeled back for separation of the lip 26 from the recess 22.

A modified form of the closure of the invention is shown in Figure 3, and in this embodiment elements of the closure corresponding to like elements of the closure of Figure 1 have been designated by the same reference numbers. In general the form of the closure of Figure 3 is basically the same as that of Figure 1, and further discussion of the former is needed only insofar as there is a variance with the latter.

It will be noted that the combined height of the shoulder 16 and flange 18 of Figure 3 is relatively greater than it is for the same elements in Figure 1, and that there is a resultant sharper change in direction of the cover panel 32, as indicated at 46. This, combined with the tautness of cover panel 32, as indicated at 48, makes for the application of a highly efficient holding force by the cover panel 32 to the flange 18, thus serving to very effectively maintain the flange 18 in seal-

ing relation to the shoulder 16. It will be further noted that I have provided the upper surface of the shoulder 16 with a seepage arrester element 50, preferably of chamois or leather, bonded or otherwise secured to the shoulder 16, and that the underside of the flange 18 is provided with a recess 52 complementary to element 50. The seepage arrester 50 is provided as an additional safeguard of a washer type to ensure against even minor moisture seepage into the location of the lip 20 and recess 22.

Additionally, the closure of Figure 3 varies from that of Figure 1 in the provision of a conventional slide fastener 54 between the lip 20 and joint 14.

- 15 The fastener 54 serves to prevent disturbance to the sealing joint constituted by the lip 20, recess 22 and panel edge joint 14, which disturbance might ensue from undue or exaggerated flexure of the closure. When the flange 18 is peeled back 20 the fastener 54 may be opened to provide access through the joint 14 to the pocket, or the like, for which the described structure serves as a closure.

What I claim as new and desire to secure by Letters Patent is:

- 25 In a sealing closure for the abutting edges of two pieces of fabric, an upstanding flattened shoulder disposed longitudinally of the first of said edges, outwardly extending lips longitudinally disposed along the upper extremities of said shoulder, the inner of said longitudinal lips forming a fluid-tight seal with a longitudinally extending recess disposed adjacent the upper extremity of the second of said edges, a laterally extending flange made integral with the upper extremity of said second edge and extending over said upstanding shoulder on said first edge, a downwardly and inwardly curved lateral strip on said flange fitting over the outer of the lips of said shoulder in fluid-tight engagement therewith, 40 and a cover strip affixed on the first of said edges close to the edge of said shoulder extending over said shoulder and flange in tight bearing relation therewith and removably affixed inwardly of said second edge.
